(57) **CLAIM**

The ornamental design for a vehicle jack platform, as shown and described.

DESCRIPTION

FIG. 1 is an isometric view of the vehicle jack platform of the present invention.

FIG. 2 is a top view of the vehicle jack platform of the present invention.

FIG. 3 is a bottom view of the vehicle jack platform of the present invention.

FIG. 4 is a front view of the vehicle jack platform of the present invention.

FIG. 5 is a rear view of the vehicle jack platform of the present invention.

FIG. 6 is a side elevation view of the vehicle jack platform of the present invention.

FIG. 7 is an opposite side elevation view shown in FIG. 6 of the vehicle jack platform of the present invention; and,

FIG. 8 is an isometric view of the vehicle jack platform of the present invention as it would be used beneath a vehicle jack. The broken line showing of a vehicle jack in FIG. 8 is included for the purpose of illustrating environment and forms no part of the claimed design.
